UNITED STATES PATENT OFFICE.

LORIN WINFIELD CANADY, OF TOYAH, TEXAS.

VENTILATOR FOR CARS.

SPECIFICATION forming part of Letters Patent No. 619,718, dated February 21, 1899.

Application filed November 8, 1897. Serial No. 657,806. (No model.)

To all whom it may concern:

Be it known that I, LORIN WINFIELD CANADY, of Toyah, in the county of Reeves and State of Texas, have invented a new and Improved Ventilator for Cars, of which the following is a full, clear, and exact description.

This invention relates to an apparatus for ventilating cars and other chambers by thermostatic regulators by means of movement-transmitting mechanism controlled by a thermostat and certain peculiarly-constructed shutters or covers by which orifices are opened and closed in accord with the conditions of the temperature.

15 This specification is the disclosure of one form of my invention, while the claim defines the actual scope of the invention.

Reference is to be had to the accompanying drawings, forming a part of this specification, 20 in which similar characters of reference indicate corresponding parts in all the figures.

Figure 1 is a sectional plan of the invention on the line 1 1 of Fig. 2. Fig. 2 is a vertical section of the invention on the line 2 25 of Fig. 1, and Fig. 3 is an elevational section on the line 3 3 of Fig. 2.

The invention is shown in connection with a railway-car. Each end of the car has two openings 5 therein, which are covered by 30 screening 6. Each opening 5 is commanded by a door or shutter 7. These doors may be provided with felt surfaces engaging around the openings 5, so as to effect a thorough closure of said openings. The doors or shutters 35 7 are respectively mounted on rods 8, rockably carried in brackets 9, secured to the car. Spiral springs 10 respectively encircle the rods 8 and serve normally to open the shutters.

40 Brackets 11, projecting in pairs from the ends of the car, respectively carry rock-shafts 12, on which cams 13 are fixed. The cams 13 are two for each rod 12, and there is one rod 12 for each shutter 7. The cams 13, bearing 45 against the shutters 7, serve to close the same or to hold the shutters at any desired position. The springs 10 act contrary to the cams 13, and consequently the shutters 7 are held firmly at the desired point and without loose 50 movement.

Secured rigidly at one side of the car and

near the roof thereof is a longitudinal beam 14. The beam 14 has two thermostatic rods 15 lying on top thereof and rigidly secured thereto, respectively, at the outer ends of the 55 rods. The remaining portions of the rods are free with reference to the beam 14, and the inner ends of the rods 15 terminate adjacent to each other and are connected with a lever 16, running horizontally beneath the 60 roof of the car and having its inner end guided by a hanger 17, supported from the roof. The expansion and contraction of the rods 15 swings the lever 16 within the hanger 17. The inner end of the lever 16 is provided with 65 a cross-bar 18, connected at its ends with the respective differentially-mounted levers 19, the arrangement being such that upon the expansion of the rods 15 the parts 16, 18, and 19 will be so moved as to throw outward the 70 upper ends of the levers 19. These outer ends of the levers 19, being respectively connected with reciprocal bars 20, move outward said bars upon the expansion of the rods 15. The two bars 20 extend, respectively, to the 75 ends of the car and are bent downward and thence horizontally, the horizontal portions forming racks 21. The racks 21 respectively mesh with pinions 22, secured, respectively, upon the two uppermost shafts 12. By these 80 means said uppermost shafts 12 are turned, and the cams 13 of said shafts are operated to control the shutters 7. The two lowermost shafts 12 are respectively controlled from the corresponding upper shafts by sprocket-chains 23, running around sprocket-wheels 24, secured one to each shaft 12. By this arrangement the shutters 7 are controlled in absolute unison with the temperature of the car, so that as the car becomes hot the shutters are opened and as the car becomes cold the shutters are closed in proportion to the reduction of the temperature.

Having thus described my invention, I claim as new and desire to secure by Letters 95 Patent—

The combination, with a structure to be ventilated, having an opening therein, of a rod rockably mounted adjacent to the lower edge of the opening, a shutter carried on the rod and capable of closing the opening, a rock-shaft extending parallel with the rod and

located above the same adjacent to the shutter, a cam attached to the rock-shaft and engaging the shutter to throw the same to closed position, a pinion fixed to the rock-shaft, and 5 a horizontal sliding bar, one end of which is bent downward and thence horizontally, and the horizontal portion being provided with

rack-teeth engaging the pinion, whereby to throw the rock-shaft.

LORIN WINFIELD CANADY.
